UNITED STATES PATENT OFFICE

2,528,984

FLUID FUEL BURNER HAVING PREHEATING
AND SUPERHEATING MECHANISM FOR
AIR AND STEAM EMPLOYED IN THE
BURNER

George Mason Wilhelm, New York, N. Y.

Application June 27, 1946, Serial No. 679,609

4 Claims. (Cl. 158—74)

1

This invention relates to fuel burners and more particularly to the type that employs fluid fuels.

One of the objects of the invention is the provision of a new and improved fluid fuel burner having provision for producing superheated steam and for introducing the same into the interior of the fuel stream for elongating the flame and for assisting in combustion.

Another object of the invention is the provision of a new and improved fluid fuel burner having novel valve means for supplying air or aqueous fluid to the flame or for simultaneously supplying both air and aqueous fluid in various proportions to the burner for assisting in burning the fluid fuel.

A still further object of the invention is the provision of a new and improved burner for generating superheated steam for discharging the same in the interior of the burning flame for assisting in the combustion of the same.

A further object of the invention is the provision of a new and improved fluid fuel burner that is provided with novel means for controlling the supply of both steam and air to the burner, the parts being so constructed that either may be supplied to the burner to the exclusion of the other, or both supplied simultaneously as may be desired.

Another object of the invention is the provision of a new and improved burner having novel means for pre-heating the fuel and discharging the same in a hollow rotating mass into the combustion chamber and simultaneously discharging superheated steam into the center of the rotating mass for assisting combustion.

A still further object of the invention is the provision of a new and improved fluid fuel burner that is simple in construction, efficient in operation, composed of few moving parts, and that is comparatively inexpensive to manufacture.

Other and further objects and advantages of the invention will appear from the following description taken in connection with the accompanying drawings, in which,

Fig. 1 is a vertical section of the burner;

Fig. 2 is a section on line 2—2 of Fig. 1;

Fig. 3 is a section on line 3—3 of Fig. 1;

Fig. 4 is a section on line 4—4 of Fig. 1;

Fig. 5 is a section on line 5—5 of Fig. 1;

Fig. 6 is a section on line 6—6 of Fig. 1;

Fig. 7 is a section on line 7—7 of Fig. 1.

Referring now to the drawings, the reference character 10 designates the burner assembly, in general, which comprises a rear or feed section 11 for supplying air and fuel to the burner; an inter-

2

mediate or central section 12 for controlling the amounts of fluid supplied to the burner; and the forward or housing section 13 for housing the preheater 14 and for forming the combustion chamber 15.

The rear section 11 comprises a fan housing 16 for housing the air fan 17 and a motor frame or casing 18 for housing the motor 19 and the oil pump 20, as will now be described. The fan housing 16 forms the rear end of the burner assembly and is a hollow casing closed at its forward end and with its rear end wall 21 provided with a peripheral flange 22 for attachment purposes and having an axial opening 23 for the air intake of the fan or blower 17. The fan 17 may be of the conventional squirrel cage type and is mounted within the hollow of the casing 16 on the armature shaft 24 of a motor assembly 19. The shaft 24 is journaled at one end in the forward end 25 of the casing 16 as shown at 26. The air enters the passage 23 into the central portion of the fan and is forced radially outwardly by centrifugal action into and along the air passage 48 provided in the housings 16, 18 and 12 of the burner assembly, as will presently appear.

The forward portion of the rear or feed section 11 of the burner assembly comprises the cup-shaped hollow motor frame or casing 18 having the end wall 21. This casing contains a motor 19 of any well known construction. The rotor 28 of the motor is mounted within the motor casing or frame 18 on the armature shaft 24 which in turn is journaled at its forward end in the front end wall 21 of the motor frame or casing 18 as at 31. Since the motor is of the usual or any well known construction, it is not thought necessary to further illustrate or describe the same any further than to state that the rotor member is shown diagrammatically at 28 and the stator at 30.

Dowel or guide pins 32 between the adjoining ends of the fan and motor casings or housings 16 and 18 position those housings relative to each other in assembling the parts. The inner or forward end of the motor casing 18 is provided with a radial attaching flange 33.

The forward side of the end wall 21 of the motor housing or frame 18 is recessed on its front side as at 34 for cooperating with a recess 35 in the rear face of a plate 36 for forming a housing for the rotor member 37 of a centrifugal oil pump 20. The rotor member 37 of the fuel pump 20 is mounted on the forward end of the armature shaft 24 and operates in the space formed by the opposed cavities 34 and 35. Since the oil pump 20 is a conventional centrifugal pump no additional

description is thought necessary further than to state that the oil is supplied to the pump from a suitable reservoir through a radial passage 39, Figs. 1 and 2, and an axial passage 41 which delivers the oil axially to the center of the pump where the blades or disc of the rotor 20 throw the same by centrifugal action into the radial opening 42 for forcing the same under pressure along the passage 43. A hand operated valve 44a may be employed for controlling the flow of oil to the burner along the passage 43. Suitable means are also provided for controlling the flow of air as will presently appear. Dowel or positioning pins 29 between the end of the wall 21 of the motor casing 18 and the plate 36 position the plate and casing 18 while the parts are being assembled.

The fan housing 16, motor frame or casing 18, and plate 36 are held in assembled relation onto the intermediate or control section 12 by the assembly bolts 44 which extend through aligned openings in a flange 45 on the section 12 and through aligned openings in the plate 36 and flange 33 and are tapped into the flange 22 of the housing 16.

In event air and fluid fuel under pressure are available the fan, pump, and motor may be omitted and the air and fuel passages 48 and 43 at the rear end of the housing 12 connected directly to the air and fuel pressure reservoirs, respectively.

The intermediate or control section 12 of the burner is in two parts comprising the rear or valve housing 47 and the front or connection housing 49. Both housings are hollow and have mating flanges 51 and 52 which are clamped together by threaded bolts 53. This section is made in two parts to facilitate assembly. Any suitable arrangement will serve the purpose. But, as shown, the housing 47 is cupshaped with its forward end closed and forming a partition 54 between the control section and the forward portion of the burner assembly. This partition 54 is provided with a central port 55 in the form of a tapered recess opening into a passage 60 extending through the partition.

Means are provided for supplying either water or air or both to the port 55 for promoting the combustion of the fuel. Such construction will now be described.

An angular fuel passage 57 is provided in the bottom wall of the housing 47. It extends radially into the partition 54 across the oil passage 43 and then forwardly through the partition as shown in Fig. 1. A hand operated valve 44a is provided for controlling the flow of fluid fuel from the pump 20 along the passages 43 and 57.

A radial air passage 74 is also provided that extends through the side wall of housing 47 across the air passage 48 into the forward end of the bore 69 of the housing 47 as shown in Fig. 1. A manually operated valve 75 controls the amount of air flowing through the passage 74 from the conduit or passage 48.

Slidably mounted within the valve housing 47 within the bore 69 thereof is the combined water and air control valve 62 which has a cone-shaped forward extension 63 that in turn is adapted to make a water and air-tight connection with the port 55 when the valve is in its extreme forward position. Spaced rearwardly from the forward end of the valve 62 is an angular passage 64 in the valve extending to the side of the valve at its rear end and at its forward end extending axially through the projection 63 as shown in Fig. 1. The housing 47 is provided with a trans-

verse water passage 65, Figs. 1 and 3, which is adapted to be connected to the water main or other source of supply of water under pressure. A valve 67, Fig. 3, may be provided for controlling the flow of water through said conduit 65. The water passage 65 is in communication with a passage or bore 68, leading into the cylinder bore 69 of valve housing 47, as at 70.

Appropriate mechanism is provided for supplying air by adjusting the valve 62 to the port 55 during the initial operation of the burner or for supplying water or water and air thereto during the final or normal operation of the burner.

In the form of construction selected to illustrate one embodiment of the invention, an air passage 74 leading from the air passage 48 to the forward end portion of the cylinder bore 69, is provided for conducting air alone to the interior of the bore 69 when the piston is moved rearwardly to the position shown in Fig. 1 where the passage 70 is closed.

The passage or port 70 which is a continuation of the water passage 68 is closed when the valve 62 is slid rearwardly to the position shown. The air passage 48 has an extension 74 that opens into the forward end of the cylinder bore 69 through the side wall of the cylinder for delivering air to the bore in front of the valve 62 when the valve 62 is slid rearwardly as shown in Fig. 1. The arrangement of the parts is such that the passage 70 may be opened while the passage 74 is closed or vice versa or both passages partly opened, one being opened while closing the other. This is accomplished by so constructing the valve 62 that the distance between the passage 64 and the front end of the valve 62 is substantially the same as the space between the passages 70 and 74. As shown, the passage 70 is closed and the passage 74 wide open, but by moving the valve 62 forwardly to its limit of movement the passage 70 will align with the passage 64 and the passage 74 be closed by valve 62 or by the projection 63 seating in the recess 55.

The valve 62 is limited in its forward movement by the end wall of the housing 12 and by the projection 63 seating in the port recess 55 and is limited in its rearward movement by contact with a resilient split retainer ring 75 seated in an annular groove in the cylinder bore 69.

The valve 62 is manually controlled by a suitable lever 77, Fig. 3, pivoted as at 78 to the housing 47. The inner end of the lever 77 is bifurcated as at 79 and the furcations are pivoted to a block 81, Figs. 1 and 3, by a pivot 82. The rear end of the valve 62 is recessed as at 83, Fig. 1, and the block 81 is pivoted at its forward end within the recess by the pivot 84, Figs. 1 and 4, which is arranged at right angle to the pivot 82 so as to provide freedom of movement of the lever and valve. Any conventional means may be provided for holding the lever in adjusted position, such as a toothed quadrant fixed on the housing 47 and a spring pressed latch carried by the lever. It will thus be seen, that the valve 62 may be moved by the lever 77 to its rearmost position as shown in Fig. 1 for opening the air passage 74 to the port 55 and closing the water passage 70 or it may be moved to its extreme forward position for closing the air passage 74 and opening wide the water passage 70 to the passage 64 or moved to intermediate positions for partially opening both passages 70 and 74 to varying extents.

Means are also provided for discharging air into the fuel preheater 14 as may be desired. For this purpose, the partition 54 is provided with

an angular air passage 71 which opens at one end into the air passage 48 and at its other end it is in communication with a conduit 58 leading to the nozzle 72 which discharges into the preheater chamber as will presently be described.

Suitable fittings or connectors 30a, 30b, and 30c, within the housing 49 are provided for connecting the air passages 56 to the conduit 58 leading to the nozzle 72; for connecting the fuel passage 57 to the fuel conduit 59 leading to the nozzle 80; and for connecting the port 55 to the rear end 61 of the super-heater coil 106 as will later be described.

The forward portion of the burner assembly comprises the housing 13 which is hollow and open at both ends. It is a cylinder and its rear end telescopes within the forward end of the housing 49 and is fixed in position therein by set screws 85 extending at intervals around the forward end of the housing 49.

Slidably mounted within the housing 13, but anchored therein, is the preheater and mixer unit 86 which comprises a spider member 87, Figs. 1 and 5, seated in a counterbore in the rear end of the housing 13 and held in position therein by a split retainer ring 88. The spider member 87 is provided with a hub portion 89 having radially extending arms or spokes 91, Fig. 5, and an axial opening 92 through the hub. The spaces between the spokes form openings through which pipes and pipe nozzles extend as will be apparent from an inspection of Fig. 5.

The spokes 91 have an integral hollow forwardly extending tapered projection 93, Fig. 1, which is in the form of a hollow truncated cone having its base concentric with the central opening 92 and integral with said spokes. The opening through the forward end of the conical projection is considerably enlarged and is of substantially the same diameter as the rotating drum of the preheater as will shortly appear.

The mixing and preheater mechanism comprises a cylinder supporting member 94 having annular flanges or spider arms 95 and 96 at its ends which engage the housing 13 and position the cylinder member 94. The forward end of the casing or housing 13 is counterbored to form an annular shoulder 97, Fig. 1, against which the arms of the outer flange or spider 96 of the supporting member 94 are seated, as clearly shown in Fig. 1, and held in such position by a spider flange 98 on the preheater 14 and by a split retainer ring 99 which is seated in a groove in the interior surface of the housing 13 and engages the flange 98. These flanges are in the form of spiders having radially extending arms or spokes between which the ends of the superheater coil 106 extend as shown in Figs. 1 and 7.

Rotatably mounted within the cylinder member 94 is a drum member 100 that is provided with inwardly extending vanes 101 which are arranged spirally on the interior surface of said drum. The drum may be provided at opposite ends with anti-friction bearings as 102. As shown, the drum rotates about a horizontal axis on ball bearings which have their races 102 seated against shoulders 102a, Fig. 1, formed by counterboring the ends of the cylindrical member 94 and against shoulders 102b formed by reducing the ends of the rotating drum 100 and held against said shoulders by split retaining rings 103 at the ends of the cylindrical support 94 and drum 100.

The preheater 14 is a hollow cylinder or core member arranged axially within the drum and is tapered and threaded at its rear end as at 104.

for connection to one end 105 of the pipe or conduit 106 that leads from the superheater 90 as shown in Fig. 1. The preheater is rigidly held axially within the drum 100 by its flange 98 on its front end which is in the form of a spider having arms or spokes extending radially outwardly of flange 96. The spider flange 96 is spaced from the drum 100 sufficiently to provide clearance for the rotation of the drum with its spiral vanes. The rotating drum is slightly spaced forwardly of the front end of the forward projection 93 of the spider 91 as shown in Fig. 1. The flange or spider 98 holds the preheater or core member 14 axially within the rotating drum 100 and the annular space between the drum 100 and preheater or core member 14 forms a preheating and mixing chamber 110 that is open at both ends and into which the liquid fuel from the fuel pump discharge passage 42 flows and is discharged therein under pressure through a nozzle 80 on the forward end of conduit 59. Nozzle 80 is flat and curved laterally to conform to the curvature of the end of the chamber 110. When desired, air under pressure is supplied to this preheater chamber 110 through the air passage 48, valve 73, air passages 56, 58 and nozzle 72. The nozzle 72 is also flattened and curved laterally to conform to the curvature of the chamber 110. The amount of air admitted is controlled by the manually operated valve 73.

A superheater 90 is provided for superheating the air or steam as it passes through the coil 90 for heating the core or preheater member 14 for preheating the fuel or fuel mixture that passes through the preheating chamber 110 and for dissociating the hydrogen and oxygen more or less in the superheating operation. As shown in Fig. 1 the superheater 90 comprises a coil of pipe 106 mounted within the combustion chamber 15 in front of preheater and mixer unit or assembly 86. The inner or rear end 61 of the coil 106 is attached to the passage 60 of the port 55 by the connector 30c and extends forwardly between the spokes or arms of the spiders 87, 95, 96 and 98 and is continuous with the superheater coil 106, of the superheater 90. The opposite or forward end 105 of the coil 106 is connected to the preheater or core member 14 as at 104 by a suitable union nut or pipe connector 109.

In Fig. 1 is shown the position of the parts of the burner assembly during the initial operation of the burner. In this position, the lever 77 has been moved forwardly for moving the valve 62 rearwardly for closing the water passage 70 and for opening the air passage 74 and opening the port 55 to the air, so that air and fuel only is fed to the burner while heating up the superheater and preheater members. Air under pressure then from the fan 17 passes along the passages 48 and 74 into the air sluice 40 formed between the valve 62 and the partition 54, and on through the port 55 into the rear end 61 of superheater coil 106 and on into said coil where it is superheated by the superheater 90 and discharged by the outer end 105 of the coil 106 into the interior of the preheater 14 for preheating the incoming fuel and air. The air is discharged forwardly from the preheater into the combustion chamber into the interior of the whirling mass of fuel where it mingles with the heated fuel and promotes combustion of said fuel.

The fuel is discharged from the pump 37 through the passages 42, 43, 57, 59 and nozzle 80 into the preheating space 110, where it im-

pings on the vanes 101 for rotating the drum 100 for rotating and atomizing the fuel. The fuel is preheated in the chamber 110 and discharged into the combustion chamber where it burns and the flame is projected forwardly by virtue of the pressure of the air.

The pressure of the air will be pressure imparted to it by the fan 17 plus the added pressure due to superheating the air which will be considerable so that the flame will be elongated forwardly for providing an extended surface contact with the boiler or other device that is being heated. During the initial operation of the burner the valve 73 may be entirely closed, or if desired, it may be partly open. If partly opened, air will be discharged from the fan 17 through passages 48, 71 and 58 and nozzle 72 into the preheater chamber 110 for mixing with the fuel preparatory to ignition in the combustion chamber 15.

After the coil 106 has become superheated, the lever 77 is moved rearwardly for moving the valve 62 forwardly for closing the air supply through the passage 74 and for alining the port 78 with the passage 64 so that water will flow from the passage 68 to the coil 106 through the passage 70, 64, and port 55 into the end 61 of coil 106 and be converted into steam and the steam superheated. Since water contains more or less free oxygen in its mass and since by superheating steam more or less of the steam particles will be disassociated into free hydrogen and oxygen, the superheated steam will pass through the preheater 14 and heat the fuel passing through the preheater chamber 110. The superheated steam will be projected forwardly in the center of the preheated rotating mass of fuel projected from the preheater chamber 110 for promoting combustion and since the steam is now under high pressure it will function like the heated air as noted above to elongate the flame forwardly beyond the end of the burner for imparting heat by flame contact to a boiler or any other object that is being heated.

By adjusting the lever 77 between its limits of movement and adjusting the valves 75 and 67 any desired proportion of air and water may be supplied to the superheater and burner for promoting combustion.

If desired, additional air may be supplied to and mixed with the fuel in the preheater chamber 110 preparatory to its discharge into the combustion chamber. This air flow is through the passages 48, 71 and 58 and nozzle 72 and the amount of air admitted is controlled by the manually operated valve 73. It will thus be seen that the fuel is preheated, that superheated air or steam is employed for preheating the fuel, that free oxygen in the water and disassociated oxygen and hydrogen of the superheated steam is utilized for promoting combustion of fuel, that fuel may be mixed with air in the preheater chamber and that air or steam or both may be superheated and discharged into the center of the rotating mass of discharged fuel for elongating the flame of the burner within the combustion chamber.

The proportionate amounts of fuel, air, and water or steam may be varied as desired for adapting the burner to different types of fluid fuels and to meet different conditions and circumstances to which the burner may be subjected.

I claim as my invention:

1. In a fluid fuel burner, a hollow casing mem-

ber, a partition for dividing said casing member into a forward compartment and a rear valve chamber, said partition having a port for said valve member, a reciprocatory valve member in said valve chamber, a rotary drum within said forward compartment having one or more internal spirally arranged vanes, a hollow core member having an open forward end within said drum, means for delivering a fluid fuel under pressure into the space between said core and drum for impinging on said vanes for rotating said drum, a coil for superheating a fluid in the forward portion of said compartment forwardly of said core and drum, one end of said coil being connected to said port in said partition and the other connected with the rear end of said hollow core member.

2. In a fluid fuel burner, a casing, a partition within said casing dividing the same into a rear valve chamber and a forward compartment, said partition having a port therethrough, a cylindrical valve member slidably mounted within said chamber and controlling said port, said casing provided with a water conduit, said casing having a compressed air conduit, said casing having an air passage in the wall of said chamber casing terminating in an air port in the wall of said chamber adjacent to said partition and having its outer end in communication with said air conduit, said casing having a water passage terminating in a water port in the wall of said chamber rearward of said air port, said valve member having a passage leading from the forward end of said valve member to a valve port on the peripheral wall of said cylindrical valve, said valve port adapted to register with said water port when said valve member is moved to its extreme forward position, a hollow core member within said compartment having a forward open end, a drum rotatable around said core member and spaced therefrom to form a fuel chamber, a coil in front of said core member within said compartment and having one end in communication with the rear end of said core and its other end in communication with said first named port, whereby when said valve member is moved rearwardly air from said air reservoir is free to pass through said air port into one end of said coil and when said valve member is moved forwardly water is free to flow into said coil from said water conduit, means for moving said valve member and means for delivering fluid fuel to said fuel chamber.

3. An oil burner comprising a casing having a cylindrical axial opening, a rotatable cylindrical oil distributor having inclined vanes on its interior, means for directing oil under pressure into said distributor against said vanes for causing said distributor to rotate, a hollow core member having its forward end open around which said distributor is rotatable and means including a valve for discharging air into the interior of said core when said valve is in one position and for delivering an aqueous fluid into said core when said valve is in another position and a coil in front of said core having one end connected to the rear end of said core and its other end connected to said valve for receiving air or aqueous fluid delivered by said valve.

4. An oil burner comprising means forming a hollow housing open at its forward end, a hollow cylindrical supporting member within said housing, a rotary open ended drum member coaxial with said supporting member, antifriction bear-

ings between said members, spirally arranged blades on the interior surface of said drum member, a preheater hollow core member open at its forward end and coaxial with said drum member and spaced inwardly therefrom to form a preheating chamber, means for superheating steam and discharging the same into said hollow core member, means for discharging liquid fuel into said preheater chamber for preheating said fuel, and means for discharging air against said vanes 10 within said preheater chamber for rotating said drum member.
